UNITED STATES PATENT OFFICE.

CHARLES SPIRO, OF NEW YORK, N. Y.

TYPE-WRITING MACHINE.

SPECIFICATION forming part of Letters Patent No. 445,333, dated January 27, 1891.

Application filed February 19, 1890, Serial No. 341,019. (No model.) Patented in England November 28, 1889, No. 19,138.

To all whom it may concern:

Be it known that I, CHARLES SPIRO, a citizen of the United States, residing at New York, in the county of New York, State of New York, have invented certain new and useful Improvements in Type-Writing Machines, (for which I have obtained Letters Patent in Great Britain, No. 19,138, dated November 28, 1889,) of which the following is to a specification, reference being had therein to the accompanying drawings.

This invention relates to type-writers, and has particular reference to an automatic ribbon-feed and an improved type-bar bracket, the whole being an improvement upon the invention disclosed in my application, Serial No. 319,736, filed August 5, 1889.

The principal objects of the invention are to minimize the cost of manufacture and at the same time retain all the advantages of the previous construction and secure others in addition.

Referring to the drawings, Figure 1 is principally a vertical section with parts in side elevation of the principal elements of a type-writing machine in which are embodied my improvements. Fig. 2 is a plan of the pattern or blank of one of two ink-ribbon-carrying standards. Fig. 3 is a plan of the ink-ribbon guard which is applied to the table portion of each standard. Fig. 4 is a perspective of a sheet-metal pawl. Fig. 5 represents in detail a portion of one of the standards and the pawl-supporting bolt or pivot. Fig. 6 is a side elevation of a portion of a type-bar and its supporting-bracket. Fig. 7 is a vertical section of the bracket and type-bar, the section-line passing through the center of the pivot; and Fig. 8 is a plan showing the ink-ribbon in position on the tables of the standards.

Like letters refer to like parts in all the figures.

A represents any suitable base; B, a key-lever; C, a universal bail extending along under the entire series of key-levers of the machine; D, the rod, against which the key-levers are drawn by springs E, so as to pivot on the rod D.

F represents the platen of the machine, and G the type-bar-supporting platform mounted

on posts G', projecting upwardly from the base in front of the platen.

The universal bail C, mounted on the cross-shaft C', is extended toward the front of the machine, so as to admit of the attachment thereto of a ribbon standard on each side thereof, in this instance by screws H', so that at each depression of a key an oscillatory movement will be communicated to the upper end or the table portion of each of the standards H for the purpose of throwing a portion of the ink-ribbon over the printing-point x on the platen and between the platen and the type x', and to do this at an instant before the type reaches the platen and to return or withdraw the ink-ribbon from said position, so as to expose each and every impression of a type immediately after it is made, and thereby to render the machine capable of doing what is known as "visible printing."

Each of the standards H is of such a conformation as to be capable of manufacture by the use of dies, thereby reducing the cost of manufacture. A suitable sheet-metal is by dies or other equivalent tools cut to the form shown in Fig. 2, or in substantially said form. The blank is then folded on the dotted line y, so as to dispose the end or table portion at substantially a right angle to the body of the standard. Preferably before such folding the standard is punched to form an oblong hole H², a slot H³, and a ribbon-groove H⁴, and, if desired, superfluous metal may be removed by forming an opening H⁵, thereby reducing the weight and therefore the momentum of the table when in operation.

I, Figs. 1 and 3, is the ribbon-guard and tension-spring, which is secured to the under surface of each of the tables by rivets I', passing through holes H⁶, formed in the table, and holes I², formed in the guard. The guard conforms in its outline in all substantial respects with the table, and has in addition thereto an extension I³, which rests beneath the ribbon, as indicated by dotted lines in Fig. 8, and over the paper on the platen F, thereby preserving the paper from becoming smeared with ink, and when the ribbon J is arranged in the slots H³ and guides H⁴ of the tables the guards, being resilient, yieldingly press upward against the ribbon, so as to clasp the

same between themselves and under the surface of the table, and thus maintain the ribbon in a smooth condition between the tables and at a point where the type comes in contact therewith. The purpose of the slots H^3 is to prevent buckling or wrinkling of the ribbon upon the tables in such movements thereof as occur when the ribbon is withdrawn from over the printing-point.

10 K represents an ink-ribbon spool having operatively connected therewith a ratchet K'. There are two of these spools employed, one being arranged on each side of a standard L, projecting upwardly from the base of the machine, and the operation is such that when one spool is being employed to wind up the ribbon the other spool pays it out, and these functions of the spools are automatically changed when an end of the ribbon is reached, 20 there being given to the ribbon a step-by-step movement during the operation of the machine. This movement is caused by the action of a pair of pawls M, only one of which is shown. These pawls consist of a piece of sheet metal having its heel M', Fig. 4, formed by bending a portion at right angles to the body of the pawl. The heel is apertured, as at M^2 for the passage of the pivot, and as at M^3 , for the reception of the end of a spring 25 M', which is secured to the outside of the standard H, and has a tendency to keep the point of the pawl in contact with the ratchet K'.

N, Fig. 5, represents the pivot-bolt, which 30 has a T-bar N' on the under surface of its head N^2 . This T-bar is shorter than the hole H^2 in the standard H, so that the pivot may be fixed in the hole at different points to cause the pawl to travel over a greater or lesser 35 number of teeth of the ratchet K' in order to adjust the distance of the step-by-step movement of the ink-ribbon. A nut N^3 is rabbed to form the bearing N^4 , on which the pawl M is mounted, the end of the nut abutting 40 against the standard H, and serving, in connection with the threaded portion of the pivot-bolt, to firmly bind the pivot in an adjusted position within the hole H^2 . A tie-bar O is mounted in holes O', formed in each 45 standard, and serves to preserve their parallelism when they are mounted on the extension of the bail C.

It now remains to describe the means employed for automatically throwing a pawl M out of contact with a ratchet K' and simultaneously throwing the companion pawl into contact with the companion ratchet at the time when an end of the ink-ribbon is reached, or, in other words, when the inking-ribbon is 50 completely or nearly unwound from one of the spools and wholly or nearly wholly wound upon the opposite spool. To produce this operation the ribbon J is conducted over a wire P, which extends through and at right 55 angles to and beyond the upright rod Q, mounted in the standard L, a set-screw P' serving to retain the wire in the rod. This

rod has a flange or collar P², which rests upon the upper face of the standard. Near the lower end of the rod Q there is another wire 70 R, extending at right angles from the rod to and against the end of detents R', which are pivoted, as at R², to the standard and provided at their free ends with an incline R³ and a notch R⁴, the latter adapted to receive 75 the wire R when the rod Q is turned by means of the wire P at its top. A flat spring R⁵ is secured to the lower end of the rod and extends beneath each of the detents R' and has a tendency to lift them. Immediately above 80 the notch R⁴ is the tooth R⁶ of the detent, which is intended to mesh with the teeth of the ratchet K' of the spool K, which is serving to wind up the ink-ribbon. In Fig. 1 the spool K is represented in position to wind up 85 the ink-ribbon, the pawl M operating the ratchet at the top and the detent R' preventing a backward movement of the ratchet and spool. It will be noticed that the pawl M is bent at M⁵, so as not to be thrown out of operation with the ratchet K' during the oscillations of the standards H, while the wire P is in the position shown in Fig. 1. Now assume that the end of the ribbon is being approached, or, in other words, that the ribbon 90 is very nearly unwound from the opposite spool to that shown in Fig. 1, and it will be seen that a tension is exerted on the ribbon between the spindle of the spool and the slot H³ of the table opposite to that shown in Fig. 100 1, and this tension takes effect on the end of the wire P opposite to that end shown in Fig. 1 to such an extent as to draw that end of the wire toward the platen, and consequently the opposite free end of that wire (seen in 105 Fig. 1) away from the platen and against the under surface of the pawl M and at the point M⁵, where it is bent, so that said pawl is lifted out of operative position with the ratchet K'. At the other end of the wire P the opposite 110 pawl is dropped into position with the opposite ratchet K'. Simultaneously the wire R at the lower end of the rod Q is swung away from the platen up the incline R³ and into the notch R⁴, whereby the detent R' and its tooth R⁶ are forced away from the ratchet K', (shown in Fig. 1,) the spring R⁵ permitting the resulting depression of the free end of the detent. The opposite end of the wire R is 115 removed from the notch of the opposite detent and down its incline R³, so that the opposite end of the spring R⁵ lifts the detent into mesh with the opposite ratchet. In this manner when either end of the inking-ribbon is reached the direction of its step-by-step 120 movement is automatically changed.

It now remains to describe the construction of the type-bar bracket, whereby cheapness in manufacture and strength and long service are secured. The type-bar S is bushed, 125 as at S', with steel or any other desired long-wearing material, and the bushing is countersunk to form a bearing in the nature of a socket on each side. The bracket T is pro-

vided with a single standard T', which is bored, as at T², for the reception of a screw or bolt, and has raised on its inner surface an annular bearing T³, which is convex in cross-section in the nature of a ball-bearing, and is therefore adapted to fit the socket of the type-bar.

U represents the bolt or screw, which fits the aperture T² in the single standard T', and which bolt is provided on the under surface of its head with a convex bearing U', adapted to fit the socket of the type-bar. The bracket is slotted at its base, as indicated by dotted lines T⁴ in Fig. 7, for adjustable connection to the bracket-platform G by means of the screws V. This platform is also apertured, as at G², for the passage of the wires or ligaments for a front series of type-bars. Forming the bracket with a single leg or standard gives access for the operation of machine-tools in the construction of the bearing. In all the various parts of the machine hereinbefore described dies and machinery for the construction of the parts can be used, insuring not only cheapness of manufacture, but uniformity and interchangeability of parts.

One of the main features of the type-bar bracket is that comparatively large stiff screws or bolts U can be employed, while the bearing itself, the most sensitive part of a type-writing machine, is large and capable of long service and is subject to uniform wear, whereby the alignment of the machine is rendered more permanent and not affected by any irregularity of the under surface or the base of the bracket or of the upper surface of the platform to which it is secured, as the bars are subjected to a preparatory jigging while in position on the platform to bring their bearings to a wearing-surface. On reference to Fig. 7 it will be observed that I leave a space surrounding the pivot-bolt between its head and the adjacent wall of the bracket to permit of adjustment to compensate for wear and to guard against frictional bearing or wearing of the parts by any dirt or foreign substances that might accidentally find ingress thereto.

What I claim as new is—

- 50 1. A standard for a ribbon-carrier having integral tables terminating in diagonal edges provided with a ribbon-guiding slot passing vertically through the table, substantially as specified.
- 55 2. A ribbon-carrier standard having an integral table provided with transverse ribbon-receiving slot and a diagonally-transverse ribbon-guide, substantially as specified.
- 60 3. The combination, with the universal bail of a type-writing machine, of a ribbon-carrier formed of two standards, each having a table provided with a ribbon-guide and a ribbon-receiving slot, substantially as specified.
- 65 4. In a ribbon-carrier, standards having tables and guards secured to the tables and projecting from the tables toward the printing-point, substantially as specified.

5. In a ribbon-carrier, the combination of slotted tables having ribbon-guides and an adjustable tension-plate bridging the ribbon for keeping the ribbon on the table free from wrinkles, substantially as specified.

6. The spool-feeding pawl formed of sheet metal and having its head bent to an angle from and in a vertical plane with its body and perforated for the reception of a pivot and also for a spring, substantially as specified.

7. A pawl formed of sheet metal and having at one edge an integral angularly-disposed head perforated for a pivot and having its body portion bent between said head and its free end, substantially as specified.

8. The combination, with a ribbon-carrier standard having an elongated aperture, of a pawl and a pawl-pivot having a T-head fitted to the opening of the standard and means for connecting the pawl and pivot with the standard, substantially as specified.

9. The combination, with a ribbon-carrier standard having an elongated opening, of a pawl, a T-headed screw-threaded pivot, and a shouldered nut, substantially as specified.

10. The combination, with ribbon-spools and a ribbon-carrier, of a pawl-and-ratchet mechanism, the pawls of which are adjustably connected to the carrier, substantially as specified.

11. The combination, with the pawl-and-ratchet mechanism of the ribbon-spools, of detents having inclined or beveled free ends, a spring having a tendency to raise said detents, and an oscillating shaft having arms for depressing said detents, substantially as specified.

12. The combination, with the pawl-and-ratchet mechanism of the ribbon-spools, of a ribbon-carrier pivotally supporting the pawls and provided with springs for keeping the points of the pawls in contact with the ratchets, and a vertical shaft having arms arranged between the carrier and the ratchets and operating to lift the pawls in opposition to the spring, substantially as specified.

13. The combination of a type-bar, a single-armed type-bar bracket, and a pivot, with a space surrounding said pivot, substantially as specified.

14. A type-bar bracket comprising a single standard having a projecting bearing, a type-bar having projecting bearings, and a pivot-bolt having a bearing agreeing with that of the type-bar, with a space surrounding the bearings, substantially as specified.

15. A type-bar bracket comprising a single standard having a projecting convex bearing, a type-bar formed with a socket to receive said bearing, and a bolt passed through the bearings and socket, with a head conforming to the socket with separated bearings, substantially as specified.

16. The combination, with the type-bar bracket having a single standard bored and having raised annular bearing convex in cross-section, of the type-bar bushed as shown and

a bolt for uniting the parts passed through the same, with the bolt portion free of the bushing, substantially as specified.

17. The combination, with the type-bar bracket having slotted base, of the type-bar, the transverse bolt, and a ball-and-socket connection between the type-bar bracket and bolt, substantially as specified.

18. In a ribbon-carrier, the combination of slotted tables having ribbon-guides and an adjustable tension-plate conforming substantially to the shape of the tables for keeping the ribbon on the tables free from wrinkles, substantially as specified.

19. In a ribbon-carrier, the combination of slotted tables having ribbon-guides and an adjustable tension-plate conforming substantially to the shape of the tables mounted thereon and bridging the ribbon for keeping the same on the table free from wrinkles, substantially as specified.

In testimony whereof I affix my signature in presence of two witnesses.

CHARLES SPIRO.
